(57) **ABSTRACT**

A hand grip mechanism includes a first member, a second member connected to the first member in a vertically moveable manner, a spring providing a biasing force to lower the second member with respect to the first member, and a hand grip configured by two grip links, each including a grip rotatably connected to the first member, a link rotatably connected to the second member below a connecting portion between the first member and the grip, and first and second connecting shafts each connecting the grip and the link below a connecting portion between the second member and the link. By a pressing operation to squeeze the hand grip against the biasing force of the spring, the grip and link in each grip link rotate relative to each other about the first connecting shaft during initial movement and about the second connecting shaft during final movement.

HAND GRIP MECHANISM, DRIVE MECHANISM, AND AIR PUMP**CROSS-REFERENCE TO RELATED APPLICATION**

The present application claims priority to Japanese Patent Application No. 2020-186154 filed on Nov. 6, 2020, the entire contents of which are incorporated herein by reference.

TECHNICAL FIELD

The present disclosure relates to a hand grip mechanism, a drive mechanism, and an air pump.

BACKGROUND

A hand grip mechanism that constitutes a drive mechanism for an air pump used for calibration of pressure equipment and the like is known. For example, see Non-patent Literature (NPL) 1. The hand grip mechanism includes a first member, a second member connected to the first member in a vertically moveable manner, a spring that provides a biasing force to lower the second member with respect to the first member, and a hand grip configured by two grip links. Each of the grip links includes a grip rotatably connected to the first member, a link rotatably connected to the second member below a connecting portion between the first member and the grip, and a connecting shaft rotatably connecting the grip and the link below a connecting portion between the second member and the link. The drive mechanism is configured by the hand grip mechanism, and a pressure chamber is formed by the first member and the second member. The pressure chamber is driven to increase or decrease in volume by manual performance of a driving operation that includes a pressing operation, to squeeze the hand grip against the biasing force of the spring, and release of the pressing operation.

CITATION LIST**Non-patent Literature**

NPL 1: Druck PV211—Pneumatic pressure and vacuum pump, GE Industrial Sensing

SUMMARY

A hand grip mechanism according to an embodiment includes:

- a first member;
- a second member connected to the first member in a vertically moveable manner;
- a spring configured to provide a biasing force to lower the second member with respect to the first member; and
- a hand grip configured by two grip links, each grip link including a grip rotatably connected to the first member, a link rotatably connected to the second member below a connecting portion between the first member and the grip, and a first connecting shaft and a second connecting shaft each connecting the grip and the link below a connecting portion between the second member and the link, wherein by a pressing operation to squeeze the hand grip against the biasing force, the grip and the link in each grip link rotate relative to each other about the first connecting

2

shaft during initial movement and rotate relative to each other about the second connecting shaft during final movement.

5 BRIEF DESCRIPTION OF THE DRAWINGS

In the accompanying drawings:

FIG. 1 is an external view of an air pump that has a drive mechanism configured by a hand grip mechanism according to 10 to a first comparative example;

FIG. 2 is a partially enlarged view of FIG. 1;

FIG. 3 is a cross-section along the A-A line in FIG. 2, illustrating the state when an actuating member is in a pressurized position;

15 FIG. 4 is a cross-sectional view illustrating the state when the actuating member has moved to a depressurized position from the state illustrated in FIG. 3;

FIG. 5 is a partial cross-sectional plan view of the drive mechanism illustrated in FIG. 1, illustrating the state before 20 a pressing operation;

FIG. 6 is a partial cross-sectional plan view illustrating the state when the pressing operation is completed from the state illustrated in FIG. 5;

FIG. 7 is a cross-sectional view of a vent mechanism 25 illustrated in FIG. 1, illustrating the state when a vent opening is opened;

FIG. 8 is a cross-sectional view illustrating the state when the vent opening is closed from the state illustrated in FIG. 7;

30 FIG. 9 is a partial cross-sectional plan view of a drive mechanism configured by a hand grip mechanism according to a second comparative example, illustrating the state before a pressing operation;

FIG. 10 is a partial cross-sectional plan view illustrating 35 the state when the pressing operation is completed from the state illustrated in FIG. 9;

FIG. 11 is a partial cross-sectional plan view of a drive mechanism configured by a hand grip mechanism according to a third comparative example, illustrating the state before 40 a pressing operation;

FIG. 12 is a partial cross-sectional plan view illustrating the state when the pressing operation is completed from the state illustrated in FIG. 11;

FIG. 13 is a partial cross-sectional plan view of a drive 45 mechanism configured by a hand grip mechanism according to an embodiment, illustrating the state at the start of initial movement;

FIG. 14 is a partial cross-sectional plan view illustrating the state when the initial movement is completed by the 50 pressing operation from the state illustrated in FIG. 13 (i.e. illustrating the state representing both completion of initial movement and the start of final movement); and

FIG. 15 is a partial cross-sectional plan view illustrating the state when the final movement is completed by the 55 pressing operation from the state illustrated in FIG. 14 (i.e. illustrating the state at completion of final movement).

DETAILED DESCRIPTION

60 There is demand for improved operability of a hand grip mechanism by a reduction in the operating force required for pressing operations.

A hand grip mechanism according to several embodiments includes a first member; a second member connected to the first member in a vertically moveable manner; a spring configured to provide a biasing force to lower the second member with respect to the first member; and a hand grip

configured by two grip links, each grip link including a grip rotatably connected to the first member, a link rotatably connected to the second member below a connecting portion between the first member and the grip, and a first connecting shaft and a second connecting shaft each connecting the grip and the link below a connecting portion between the second member and the link, wherein by a pressing operation to squeeze the hand grip against the biasing force, the grip and the link in each grip link rotate relative to each other about the first connecting shaft during initial movement and rotate relative to each other about the second connecting shaft during final movement. According to such a configuration, the positions of the first connecting shaft and second connecting shaft are set appropriately, thereby reducing the operating force required for the pressing operation and improving operability.

In an embodiment, a downward angle formed by a straight line passing through one second connecting shaft and the connecting portion between the link, connected to the one second connecting shaft, and the second member, and a straight line passing through the other second connecting shaft and the connecting portion between the link, connected to the other second connecting shaft, and the second member is larger than a downward angle formed by a straight line passing through one first connecting shaft and the connecting portion between the link, connected to the one first connecting shaft, and the second member, and a straight line passing through the other first connecting shaft and the connecting portion between the link, connected to the other first connecting shaft, and the second member. According to such a configuration, the operating force required for the pressing operation can more reliably be reduced to improve operability.

In an embodiment, in each grip link, the connecting portion between the second member and the link is provided farther inward than the central axis of the hand grip when viewed from the grip link. According to such a configuration, the operating force required for the pressing operation can more reliably be reduced to improve operability.

A drive mechanism according to several embodiments is configured by the hand grip mechanism, and a pressure chamber is formed by the first member and the second member. According to such a configuration, the operability of the hand grip mechanism can be improved.

In an embodiment, the first member includes a cylinder, and the second member includes a piston. According to such a configuration, a drive mechanism can be formed with a simple structure.

An air pump according to several embodiments includes the drive mechanism. According to such a configuration, the operability of the hand grip mechanism can be improved.

In an embodiment, the air pump includes a flow path switching mechanism including an actuating member provided with a valve body, and a housing provided with a valve chamber configured to house the valve body in an advanceable and retractable manner between a pressurized position and a depressurized position, the valve body being configured to enable an intake port to communicate with an inlet and enable an outlet to communicate with a connecting port in the pressurized position, and to enable the connecting port to communicate with the inlet and enable the outlet to communicate with the exhaust port in the depressurized position, and the pressure chamber is configured to communicate with the inlet and the outlet. According to such a configuration, the flow path switching mechanism enables

the operating specification of the air pump to be switched between a pressurizing specification and a depressurizing specification.

In an embodiment, the air pump includes a vent opening configured to communicate with the connecting port of the flow path switching mechanism both when the actuating member is in the pressurized position and in the depressurized position, and an opening and closing member configured to open and close the vent opening. According to such a configuration, the positive or negative pressure imparted to the internal space of the object by the air pump can be weakened and eliminated by opening the vent opening with the opening and closing member.

According to the present disclosure, a hand grip mechanism, a drive mechanism, and an air pump with improved operability can be provided.

Embodiments of the present disclosure are described below with reference to the drawings. The same reference sign is appended to corresponding elements across drawings.

First, a comparative example will be described. A drive mechanism **20** configured by a hand grip mechanism **20a** according to a first comparative example illustrated in FIG. **1** is a mechanism for driving a manually operated air pump **1**. The air pump **1** includes a flow path switching mechanism **10**, a drive mechanism **20**, and a vent mechanism **30**.

As illustrated in FIGS. **1** to **4**, the flow path switching mechanism includes an actuating member **11** provided with a valve body **11a**, and a housing **12** provided with a valve chamber **12a** configured to house the valve body **11a** in an advanceable and retractable manner between a pressurized position (see FIG. **3**) and a depressurized position (see FIG. **4**). The valve chamber **12a** includes an exhaust port **12b**; an outlet **12c** disposed in front of the exhaust port **12b**, in the direction from the pressurized position towards the depressurized position (for the sake of explanation, the direction from the pressurized position towards the depressurized position is defined as “in front” or “forward” in the flow path switching mechanism **10**); a connecting port **12d** disposed in front of the outlet **12c**; an inlet **12e** disposed in front of the connecting port **12d**; and an air intake **12f** disposed in front of the inlet **12e**. The valve body **11a** is configured to enable the intake port **12f** to communicate with the inlet **12e** and enable the outlet **12c** to communicate with the connecting port **12d** in the pressurized position, and to enable the connecting port **12d** to communicate with the inlet **12e** and enable the outlet **12c** to communicate with the exhaust port **12b** in the depressurized position.

The housing **12** includes the valve chamber **12a** that is provided with a cylindrical inner peripheral surface centered on a first central axis **O1** extending along the front-back direction. The air intake **12f** is provided at the front end of the valve chamber **12a**. The air intake **12f** is the back end (downstream end) of an air intake passage **12g** extending in the front-back direction. The front end (upstream end) of the air intake passage **12g** opens to an external space **S**. The exhaust port **12b** is provided at the back end of the valve chamber **12a**. The exhaust port **12b** is the front end (upstream end) of an exhaust passage **12h** extending in the front-back direction. The back end (downstream end) of the exhaust passage **12h** opens to the external space **S**. The inlet **12e**, the connecting port **12d**, and the outlet **12c** are provided on the inner peripheral surface of the valve chamber **12a**. The inlet **12e** is the radially inner end of an inflow passage **12i** extending in the radial direction. The connecting port **12d** is the radially inner end of a connecting channel **12j**.

extending in the radial direction. The outlet 12c is the radially inner end of an outflow passage 12k extending in the radial direction.

The housing 12 includes a housing body 121, a first end member 12m, and a second end member 12n. The housing body 121 includes a front-back middle portion of the valve chamber 12a, the inflow passage 12i, the connecting channel 12j, and the outflow passage 12k. The first end member 12m includes the air intake passage 12g and the front end of the valve chamber 12a. The second end member 12n includes the exhaust passage 12h and the back end of the valve chamber 12a. The first end member 12m and the second end member 12n are each integrally connected to the housing body 121 by means such as fitting, mating, screw coupling, or welding.

The valve body 11a includes an annular first sealing portion 11b in close contact with the inner peripheral surface of the valve chamber 12a and a second sealing portion 11c provided behind the first sealing portion 11b in close contact with the inner peripheral surface of the valve chamber 12a. The first sealing portion 11b and the second sealing portion 11c are each formed by an annular elastic member that is integrally connected to the valve body 11d.

The actuating member 11 includes a front shaft member 11e integrally connected to the front end of the valve body 11a and a back shaft member 11f integrally connected to the back end of the valve body 11a. The front shaft member 11e and the back shaft member 11f each extend along the front-back direction. The front shaft member 11e can be advanced or retracted inside the air intake passage 12g by the actuating member 11 advancing or retracting. The back shaft member 11f can be advanced or retracted inside the exhaust passage 12h by the actuating member 11 advancing or retracting.

When the actuating member 11 is in the pressurized position (see FIG. 3), the first sealing portion 11b is disposed at a position behind the inlet 12e and in front of the connecting port 12d, and the second sealing portion 11c is disposed at a position behind the outlet 12c and in front of the exhaust passage 12h. When the actuating member 11 is in the depressurized position (see FIG. 4), the first sealing portion 11b is disposed at a position behind the air intake 12f and in front of the inlet 12e, and the second sealing portion 11c is disposed at a position behind the connecting port 12d and in front of the outlet 12c.

By a rod-shaped tool being inserted into the exhaust passage 12h and to push the back shaft member 11f of the actuating member 11 forward, the actuating member 11 can be moved from the pressurized position to the depressurized position. Furthermore, by a rod-shaped tool being inserted into the air intake passage 12g to push the front shaft member 11e of the actuating member 11 backwards, the actuating member 11 can be moved from the depressurized position to the pressurized position.

By the actuating member 11 being moved to the pressurized position, the operating specification of the air pump 1 can be set to a pressurizing specification. Furthermore, by the actuating member 11 being moved to the depressurized position, the operating specification of the air pump 1 can be set to a depressurizing specification.

As illustrated in FIGS. 5 and 6, the hand grip mechanism 20a includes a first member 21, a second member 22 connected to the first member 21 in a vertically moveable manner, a spring 23 that provides a biasing force to lower the second member 22 with respect to the first member 21 (for the sake of explanation, the direction of the biasing force provided by the spring 23 is defined as "downward" or

"below" in the hand grip mechanism 20a), and a hand grip 24 configured by two grip links 24a. Each of the grip links 24a includes a grip 24b rotatably connected to the first member 21, a link 24d rotatably connected to the second member 22 below a connecting portion 24c between the first member 21 and the grip 24b, and a connecting shaft 24f rotatably connecting the grip 24b and the link 24d below a connecting portion 24e between the second member 22 and the link 24d. The drive mechanism 20 is configured by the hand grip mechanism 20a, and a pressure chamber 25 is formed by the first member 21 and the second member 22.

The first member 21 is configured by a cylinder 21a and a bottom member 21b. In each of the grip links 24a, the upper end of the grip 24b is rotatably connected to the bottom member 21b via the connecting portion 24c.

The second member 22 is configured by a piston 22a and a central shaft member 22b. The central shaft member 22b has a second central axis O2 extending vertically. The second central axis O2 is perpendicular to the first central axis O1. The piston 22a is integrally connected to the upper end of the central shaft member 22b. In each of the grip links 24a, the upper end of the grip 24d is rotatably connected to the lower end of the central shaft member 22b via the connecting portion 24e.

The cylinder 21a includes a top wall 21e, provided with an entrance hole 21c that communicates with the inlet 12e and an exit hole 21d that communicates with the outlet 12c, and a peripheral wall 21f hanging down from the top wall 21e. The bottom member 21b is integrally connected to the lower end of the peripheral wall 21f. The bottom member 21b includes a through hole through which the central shaft member 22b passes. The lower portion of the central shaft member 22b includes a step 22c that expands in diameter downwards, and a coiled spring 23 is disposed between the step 22c and the bottom member 21b, coaxially with the second central axis O2.

The piston 22a is slidable in the vertical direction on the inner peripheral surface of the peripheral wall 21f of the cylinder 21a. The pressure chamber 25 is formed by the cylinder 21a (the lower surface of the top wall 21e and the inner peripheral surface of the peripheral wall 21f) and the piston 22a. Accordingly, the pressure chamber 25 communicates with both the inlet 12e and the outlet 12c and is driven by the hand grip mechanism 20a to increase or decrease in volume.

The two grip links 24a face each other across the second central axis O2 and have a substantially symmetrical structure across the second central axis O2. In other words, the second central axis O2 is also the central axis of the hand grip 24. Each connecting portion 24c connects the grip 24b and the first member 21 rotatably about a rotation axis P. Each connecting portion 24e connects the second member 22 and the link 24d rotatably about a rotation axis Q. Each connecting shaft 24f connects the grip 24b and the link 24d rotatably about a rotation axis R. The rotation axis P, the rotation axis Q, and the rotation axis R are parallel to each other. Each rotation axis Q intersects the second central axis O2.

In each grip link 24a, the connecting portion 24c between the grip 24b and the first member 21 is, for example, configured by a rotation shaft fixed to the grip 24b, the connecting portion 24e between the second member 22 and the link 24d is, for example, configured by a rotation shaft fixed to the second member 22, and the connecting shaft 24f between the grip 24b and the link 24d is, for example, fixed to the grip 24b.

Accordingly, by the pressing operation to squeeze the hand grip 24 against the biasing force of the spring 23, a pressing force F_a in the direction from the connecting shaft 24f (rotation axis R) at the lower end of the link 24d to the connecting portion 24e (rotation axis Q) at the upper end of the link 24d is applied to the connecting portion 24e in each grip link 24a. As a result, an upward combined force F of these pressing forces F_a is applied to the second member 22, thereby raising the second member 22 relative to the first member 21 to reduce the volume of the pressure chamber 25. Furthermore, by the pressing operation being released, the second member 22 can be lowered relative to the first member 21 by the biasing force of the spring 23 to increase the volume of the pressure chamber 25.

In this way, the pressure chamber 25 is driven to increase or decrease the volume manually, more specifically by the hand grip 24 being squeezed against the biasing force of the spring 23, and even more specifically by performance of a driving operation including a pressing operation, to squeeze the hand grip 24 against the biasing force of the spring 23, and release of the pressing operation.

The air pump 1 includes a first check valve, not illustrated, that permits air to flow from the inlet 12e into the pressure chamber 25 while preventing air from flowing out of the pressure chamber 25 into the inlet 12e, and a second check valve, not illustrated, that permits air to flow from the pressure chamber 25 into the outlet 12c while preventing air from flowing out of the outlet 12c into the pressure chamber 25. The first check valve is, for example, provided between the inflow passage 12i and the entrance hole 21c. The second check valve is, for example, provided between the outflow passage 12k and the exit hole 21d.

As illustrated in FIGS. 7 to 8, the vent mechanism 30 includes a vent opening 31 that communicates with the connecting port 12d of the flow path switching mechanism 10 both when the actuating member 11 is in the pressurized position and in the depressurized position, and an opening and closing member 32 configured to open and close the vent opening 31.

The vent opening 31 is formed by a sealing member 34 that is held in a block 33. The opening and closing member 32 opens and closes the vent opening 31 by close contact with and separation from the sealing member 34.

The opening and closing member 32 can be advanced or retracted between an open position (see FIG. 7) to open the vent opening 31 and a closed position (see FIG. 8) to close the vent opening 31. The opening and closing member 32 includes a first screw portion 32a, which is a screwing portion that screws into the block 33 over the entire distance between the open position and the closed position, and a shaft body 32b that connects to the end at the front (for the sake of explanation, the direction from the open position towards the closed position is defined as "front" or "forward" in the vent mechanism 30) of the first screw portion 32a (i.e. connects to the front end of the first screw portion 32a) in the direction from the open position towards the closed position and that can be advanced or retracted together with the first screw portion 32a. The first screw portion 32a has a third central axis O3 and can be advanced or retracted in the front-back direction along the third central axis O3 by rotating about the third central axis O3. The shaft body 32b is separated from the sealing member 34 in the open position to open the vent opening 31 and is in close contact with the sealing member 34 in the closed position to close the vent opening 31.

The shaft body 32b is integrally connected to the first screw portion 32a. The shaft body 32b may be configured to

be connected to the first screw portion 32a so as to be rotatable relative to the first screw portion 32a about the third central axis O3.

The shaft body 32b includes an equal-diameter portion 32c with a constant outer diameter, and a reduced-diameter portion 32d that is connected to the front end of the equal-diameter portion 32c and decreases in outer diameter toward the front. The reduced-diameter portion 32d forms the front end of the shaft body 32b. The sealing member 34 has an annular shape and is elastic. By the opening and closing member 32 advancing from the open position to the closed position, the shaft body 32b comes into close contact with the sealing member 34 at the reduced-diameter portion 32d, thereby closing the vent opening 31.

The opening and closing member 32 is connected to the back end of the first screw portion 32a and includes a first operated portion 32e that is an operated portion rotatable together with the first screw portion 32a. The first operated portion 32e is configured by a first grip 32f, which is a grip rotatable together with the first screw portion 32a. The first operated portion 32e is connected to the back end of the first screw portion 32a via a shaft 32g that has a smaller diameter than the first operated portion 32e.

The first operated portion 32e is integrally connected to the first screw portion 32a. The first operated portion 32e may be configured to be connected to the first screw portion 32a in a relatively moveable manner in the front-back direction.

The block 33 includes a retaining cylinder 33b provided with a first screwed portion 33a, which is a screwed portion into which the first screw portion 32a screws, a first set screw 33c, a base member 33d, a lid member 33e, a cover member 33f, and a washer 33g. The retaining cylinder 33b has a cylindrical shape coaxial with the third central axis O3 and is provided with the first screwed portion 33a on the inner peripheral surface. The first set screw 33c has a cylindrical shape coaxial with the third central axis O3. The outer peripheral surface of the first set screw 33c screws into the tip of the inner peripheral surface of the retaining cylinder 33b. The inner peripheral surface of the retaining cylinder 33b includes a step 33h that expands in diameter toward the front, and the sealing member 34 is sandwiched between this step 33h and the back end of the first set screw 33c.

The base member 33d includes a housing recess 33i that houses the front end of the retaining cylinder 33b and a communication channel 33j for the vent opening 31 to communicate with the connecting port 12d of the flow path switching mechanism 10. The housing recess 33i is closed by an annular lid member 33e provided with a first through hole 33k, which is a through hole through which the retaining cylinder 33b passes. The cover member 33f is provided with a second through hole 33l, which is a through hole through which the retaining cylinder 33b passes, and covers the lid member 33e and a majority of the base member 33d. The washer 33g has an annular shape provided with a third through hole 33m, which is a through hole through which the shaft portion 32g of the opening and closing member 32 passes. The washer 33g is attached to the back end surface of the retaining cylinder 33b. The washer 33g is made of synthetic resin, for example, and has elasticity enabling compression in the front-back direction. In the closed position, the washer 33g is sandwiched and compressed between the front end surface of the first operated portion 32e and the back end surface of the retaining cylinder 33b. The outer peripheral surface of the retaining cylinder 33b is provided with a third sealing portion 33n, which is a sealing portion

that closely contacts the inner peripheral surface of the housing recess $33i$. The third sealing portion $33n$ is configured by an annular elastic member that is integrally connected to a retaining member body $33o$.

The first screw portion $32a$ and the first screwed portion $33a$ are right-hand threads. The first screw portion $32a$ and the first screwed portion $33a$ may, however, be left-hand threads. The first screw portion $32a$ has a male thread, and the first screwed portion $33a$ has a female thread. The thread shape and the like of the male thread and the female thread can be set as appropriate. The first screw portion $32a$ and the first screwed portion $33a$ may be intermittent screws in which the threads are provided intermittently.

When the opening and closing member 32 is in the open position, the vent opening 31 is connected to the external space S through the ventilation channel 35 . The ventilation channel 35 is configured by a gap between the opening and closing member 32 and the retaining cylinder $33b$, which includes a non-illustrated gap between the first screw portion $32a$ and the first screwed portion $33a$. A ventilation channel that connects the vent opening 31 to the external space S when the opening and closing member 32 is in the open position may be provided instead of or in addition to the ventilation channel 35 .

The air pump 1 is used by connecting the connecting channel $12j$ to the end of an internal space of a non-illustrated object to pressurize or depressurize the internal space.

When the drive mechanism 20 is driven so as to drive the pressure chamber 25 while the operating specification of the air pump 1 has been set to the pressurizing specification, the air pump 1 can send air from the external space S to the internal space of the object through the air intake $12f$, the inflow passage $12i$, the entrance hole $21c$, the pressure chamber 25 , the exit hole $21d$, the outflow passage $12k$, and the connecting channel $12j$ in this order to pressurize the internal space of the object. When the drive mechanism 20 is driven so as to drive the pressure chamber 25 while the operating specification of the air pump 1 has been set to the depressurizing specification, the air pump 1 can send air from the internal space of the object to the external space S through the connecting channel $12j$, the inflow passage $12i$, the entrance hole $21c$, the pressure chamber 25 , the exit hole $21d$, the outflow passage $12k$, and the exhaust port $12b$ in this order to depressurize the internal space of the object.

The positive or negative pressure imparted to the internal space of the object by the air pump 1 can be weakened and eliminated by operating the opening and closing member 32 of the vent mechanism 30 to open the vent opening 31 .

The air pump 1 has a non-illustrated calibration flow path for connecting a first pressure device, which is a pressure device such as a pressure gauge and serves as an object, to an end of an internal space of a second pressure device, which is a pressure device such as a pressure gauge that serves as a reference for calibrating the first pressure device. The calibration flow path is provided to communicate with the connecting port $12d$ of the flow path switching mechanism 10 when the actuating member 11 is in both the pressurized position and the depressurized position.

To calibrate the first pressure device, the end of the internal space of the first pressure device is connected to the connecting channel $12j$, and the end of the internal space of the second pressure device is connected to the calibration flow path. Therefore, the first pressure device can be calibrated by using the air pump 1 to apply the same positive or negative pressure to the first pressure device and the second pressure device.

There is demand for improved operability of the hand grip mechanism $20a$ of the present comparative example by a reduction in the operating force required for the pressing operation, in particular the operating force required at the end of the pressing operation.

One way to meet such demand could, for example, be to set a larger distance for each grip link $24a$ between the rotation axis R of the connecting shaft $24f$ and the rotation axis Q of the connecting portion $24e$ that connects the second member 22 and the link $24d$, and to set a smaller link angle θ , which is the downward angle formed by a straight line passing through the rotation axis R of one connecting shaft $24f$ and the rotation axis Q of the connecting portion $24e$ between the link $24d$, connected to the one connecting shaft $24f$, and the second member 22 , and a straight line passing through the rotation axis R of the other connecting shaft $24f$ and the rotation axis Q of the connecting portion $24e$ between the link $24d$, connected to the other connecting shaft $24f$, and the second member 22 , as in the hand grip mechanism $20a$ according to the second comparative example illustrated in FIGS. 9 and 10. In this case, however, the stroke amount X of the lifting stroke of the second member 22 relative to the first member 21 is reduced.

A way to reduce the operating force required at the end of the pressing operation while ensuring the stroke amount X could, for example, be to provide, for each grip link $24a$, the rotation axis Q of the connecting portion $24e$ that connects the second member 22 and the link $24d$ farther inward than the second central axis $O2$, which is the central axis of the hand grip 24 , when viewed from the grip link $24a$ (that is, on the side where the connecting shaft $24f$ is positioned when viewed from a plane that includes the second central axis $O2$ and is parallel to the rotation axis R of the connecting shaft $24f$), as in the hand grip mechanism $20a$ according to the third comparative example illustrated in FIGS. 11 and 12. In this case, however, the link angle θ at the start of the pressing operation becomes larger, increasing the operating force required at the start of the pressing operation.

The embodiment of the present disclosure described below can improve operability over the above-described first comparative example by reducing the operating force required for the pressing operation, in particular the operating force required at the end of the pressing operation. More specifically, the embodiment of the present disclosure can improve operability by reducing the operating force required at the end of the pressing operation without increasing the operating force required at the start of the pressing operation, while ensuring the stroke amount X .

In the hand grip mechanism $20a$ of one embodiment illustrated in FIGS. 13 to 15, each grip link $24a$ includes a first connecting shaft $24g$ and a second connecting shaft $24h$ that each connect the grip $24b$ and the link $24d$ below the connecting portion $24e$ that connects the second member 22 and the link $24d$, instead of including the connecting shaft $24f$ that rotatably connects the grip $24b$ and the link $24d$ below the connecting portion $24e$ that connects the second member 22 and the link $24d$. Also, in the hand grip mechanism $20a$ according to the present embodiment, the grip $24b$ and the link $24d$ in the respective grip links $24a$ rotate relative to each other, as a result of the pressing operation, about a rotation axis $R1$, which is the central axis of the first connecting shaft $24g$, during initial movement and rotate relative to each other about a rotation axis $R2$, which is the central axis of the second connecting shaft $24h$, during final movement. Furthermore, in the hand grip mechanism $20a$ according to the present embodiment, in each of the grip links $24a$, the rotation axis Q of the

connecting portion 24e that connects the second member 22 and the link 24d is provided farther inward than the second central axis O2, which is the central axis of the hand grip 24, when viewed from the grip link 24a (that is, on the side where the first connecting shaft 24g is positioned when viewed from a plane that includes the second central axis O2 and is parallel to the rotation axis R1 of the first connecting shaft 24g).

Apart from these points, the hand grip mechanism 20a according to the present embodiment has a similar configuration to that of the hand grip mechanism 20a according to the first comparative example. The air pump 1 according to the present embodiment has a similar configuration to that of the air pump 1 according to the first comparative example in other respects.

As illustrated in FIGS. 13 to 15, in the present embodiment, the first connecting shaft 24g and the second connecting shaft 24h are fixed to the respective grips 24b in the grip links 24a. The rotation axis R1, which is the central axis of each first connecting shaft 24g, and the rotation axis R2, which is the central axis of each second connecting shaft 24h, are respectively parallel to the rotation axis P and the rotation axis Q.

In each of the grip links 24a, the lower end of the link 24d includes a first guiding portion 24i that guides the second connecting shaft 24h in the circumferential direction of the rotation axis R1 of the first connecting shaft 24g to cause the grip 24b and the link 24d to rotate relative to each other about the rotation axis R1 of the first connecting shaft 24g (see FIGS. 13 and 14) during the initial movement by the pressing operation. The first guiding portion 24i is configured as a cutout in the shape of an elongated hole. The first guiding portion 24i may be configured as a cutout in a shape other than that of an elongated hole.

In each of the grip links 24a, the lower end of the link 24d includes a second guiding portion 24j that guides the first connecting shaft 24g in the circumferential direction of the rotation axis R2 of the second connecting shaft 24h to cause the grip 24b and the link 24d to rotate relative to each other about the rotation axis R2 of the second connecting shaft 24h (see FIGS. 14 and 15) during the final movement by the pressing operation. The second guiding portion 24j is configured as a cutout in the shape of an elongated hole. The second guiding portion 24j may be configured as a cutout in a shape other than that of an elongated hole.

In each of the grip links 24a, the first connecting shaft 24g and the second connecting shaft 24h may be fixed to the link 24d, and the first guiding portion 24i and the second guiding portion 24j may be provided in the grip 24b.

In the present embodiment, as illustrated in FIGS. 13 and 14, the grip 24b and the link 24d can be rotated relative to each other about the first connecting shaft 24g (rotation axis R1) from the start of initial movement by the pressing operation to the end of initial movement in each of the grip links 24a, and as illustrated in FIGS. 14 to 15, the grip 24b and the link 24d can be rotated relative to each other about the second connecting shaft 24h (rotation axis R2) from the start of initial movement by the pressing operation to the end of initial movement in each of the grip links 24a. Therefore, according to the present embodiment, appropriately setting the positions of the first connecting axis 24g and the second connecting axis 24h enables an increase in the stroke amount obtained by the final movement by switching the center of rotation from the first connecting shaft 24g (rotation axis R1) to the second connecting shaft 24h (rotation axis R2) at the start of the final movement, which is at the end of the initial movement. In other words, a first link angle θ_1 at the

start of the initial movement or a second link angle θ_2 at the start of the final movement can be set smaller in correspondence with the increase in the stroke amount, achieving a decrease in the operating force required for the pressing operation.

Here, the first link angle θ_1 is the downward angle formed by a straight line passing through one first connecting shaft 24g (rotation axis R1) and the connecting portion 24e (rotation axis Q) between the link 24d, connected to the one 10 first connecting shaft 24g, and the second member 22, and a straight line passing through the other first connecting shaft 24g (rotation axis R1) and the connecting portion 24e (rotation axis Q) between the link 24d, connected to the other first connecting shaft 24g, and the second member 22. 15 The second link angle θ_2 is the downward angle formed by a straight line passing through one second connecting shaft 24h (rotation axis R2) and the connecting portion 24e (rotation axis Q) between the link 24d, connected to the one second connecting shaft 24h, and the second member 22, 20 and a straight line passing through the other second connecting shaft 24h (rotation axis R2) and the connecting portion 24e (rotation axis Q) between the link 24d, connected to the other second connecting shaft 24h, and the second member 22.

In the present embodiment, according to the above configuration, operability of the initial movement is maintained with an equivalent link angle θ (first link angle θ_1) at the start of the initial movement as in the first comparative example, while ensuring a stroke amount X equivalent to 30 that of the first comparative example, and operability of the final movement is improved by reducing the link angle θ (second link angle θ_2) at the end of the final movement as compared to the first comparative example.

The aforementioned effect can be obtained more reliably 35 by setting the positions of the first connecting shaft 24g and the second connecting shaft 24h so that the second link angle θ_2 is larger than the first link angle θ_1 at the start of the final movement, which is the end of the initial movement.

In the present embodiment, in each of the grip links 24a, 40 the rotation axis Q of the connecting portion 24e that connects the second member 22 and the link 24d is provided farther inward than the second central axis O2 when viewed from the grip link 24a. This makes it easier to set a smaller link angle θ (second link angle θ_2) at the end of the final movement, more reliably enabling improvement in operability.

In the present embodiment, each of the grip links 24a has only two connecting shafts (the first connecting shaft 24g and the second connecting shaft 24h) that connect the grip 24b and the link 24d. Each of the grip links 24a may, however, be configured to have three or more connecting shafts that connect the grip 24b and the link 24d. For example, a configuration may be adopted in which each of the grip links 24a includes a first connecting shaft 24g, a second connecting shaft 24h, and a third connecting shaft 55 that each connect the grip 24b and the link 24d, and the grip 24b and the link 24d in each of the grip links 24a may rotate relative to each other about the first connecting shaft 24g during the initial movement by the pressing operation, about the third connecting shaft from the end of the initial movement until the start of the final movement, and about the second connecting shaft 24h during the final movement.

Various modifications may be made in the present embodiment, as long as the flow path switching mechanism 60 includes the actuating member 11 provided with the valve body 11a, and the housing 12 provided with the valve chamber 12a configured to house the valve body 11a in an

advanceable and retractable manner between the pressurized position and the depressurized position, and the valve body 11a is configured to enable the intake port 12f to communicate with the inlet 12e and enable the outlet 12c to communicate with the connecting port 12d in the pressurized position, and to enable the connecting port 12d to communicate with the inlet 12e and enable the outlet 12c to communicate with the exhaust port 12b in the depressurized position. Various modifications may also be made in the present embodiment as long as the vent mechanism 30 includes the vent opening 31 that communicates with the connecting port 12d of the flow path switching mechanism 10 both when the actuating member 11 is in the pressurized position and in the depressurized position, and the opening and closing member 32 configured to open and close the vent opening 31.

The above embodiment is an example of the present disclosure, and a variety of modifications may be made.

For example, the hand grip mechanism 20a, the drive mechanism 20, and the air pump 1 according to the above embodiment can be modified in various ways as described below.

Various modifications may be made to the hand grip mechanism 20a according to the above embodiment as long as the hand grip mechanism 20a includes the first member 21, the second member 22 connected to the first member 21 in a vertically moveable manner, the spring 23 configured to provide a biasing force to lower the second member 22 with respect to the first member 21, and the hand grip 24 configured by the two grip links 24a, each grip link 24a including the grip 24b rotatably connected to the first member 21, the link 24d rotatably connected to the second member 22 below the connecting portion 24c between the first member 21 and the grip 24b, and the first connecting shaft 24g and the second connecting shaft 24h each connecting the grip 24b and the link 24d below the connecting portion 24e between the second member 22 and the link 24d, and by a pressing operation to squeeze the hand grip 24 against the biasing force, the grip 24b and the link 24d in each grip link 24a rotate relative to each other about the first connecting shaft 24g during initial movement and rotate relative to each other about the second connecting shaft 24h during final movement.

At the start of final movement, however, the downward angle (second link angle 02) formed by a straight line 45 passing through one second connecting shaft 24h and the connecting portion 24e between the link 24d, connected to the one second connecting shaft 24h, and the second member 22, and a straight line passing through the other second connecting shaft 24h and the connecting portion 24e between the link 24d, connected to the other second connecting shaft 24h, and the second member 22 is preferably larger than the downward angle (first link angle 01) formed by a straight line passing through one first connecting shaft 24g and the connecting portion 24e between the link 24d, connected to the one first connecting shaft 24g, and the second member 22, and a straight line passing through the other first connecting shaft 24g and the connecting portion 24e between the link 24d, connected to the other first connecting shaft 24g, and the second member 22.

In each grip link 24a, the connecting portion 24e between the second member 22 and the link 24d is preferably provided farther inward than the central axis (second central axis O2) of the hand grip 24 when viewed from the grip link 24a.

Various modifications may be made to the drive mechanism 20 according to the above embodiment as long as the

drive mechanism 20 is configured by the hand grip mechanism 20a, and the pressure chamber 25 is formed by the first member 21 and the second member 22.

In the drive mechanism 20, however, the first member 21 preferably includes the cylinder 21a, and the second member 22 preferably includes the piston 22a.

The air pump 1 according to the above embodiment can be modified in various ways as long as the air pump 1 includes the drive mechanism 20.

The air pump 1, however, preferably includes the flow path switching mechanism 10, which includes the actuating member 11 provided with the valve body 11a, and the housing 12 provided with the valve chamber 12a configured to house the valve body 11a in an advanceable and retractable manner between the pressurized position and the depressurized position, the valve body 11a being configured to enable the intake port 12f to communicate with the inlet 12e and enable the outlet 12c to communicate with the connecting port 12d in the pressurized position, and to enable the connecting port 12d to communicate with the inlet 12e and enable the outlet 12c to communicate with the exhaust port 12b in the depressurized position. The pressure chamber 25 preferably communicates with the inlet 12e and the outlet 12c.

Furthermore, the air pump 1 preferably includes the vent opening 31 configured to communicate with the connecting port 12d of the flow path switching mechanism 10 both when the actuating member 11 is in the pressurized position and in the depressurized position, and the opening and closing member 32 configured to open and close the vent opening 31.

The invention claimed is:

1. A hand grip mechanism comprising:
a first member;
a second member connected to the first member in a vertically moveable manner;
a spring configured to provide a biasing force to lower the second member with respect to the first member; and
a hand grip configured by two grip links, each grip link comprising:

a grip rotatably connected to the first member,
a link rotatably connected to the second member below a first connecting portion between the first member and the grip, and
a first connecting shaft and a second connecting shaft each connecting the grip and the link below a second connecting portion between the second member and the link,

wherein by a pressing operation to squeeze the hand grip against the biasing force, the grip and the link in each grip link rotate relative to each other about the first connecting shaft during initial movement and rotate relative to each other about the second connecting shaft during final movement,

wherein a second downward angle is formed by a first straight line passing through a first second connecting shaft and the second connecting portion between the respective link, connected to the first second connecting shaft, and the second member, and a second straight line passing through a second second connecting shaft and the second connecting portion between the respective link, connected to the second second connecting shaft, and the second member; wherein the second downward angle is larger than a first downward angle formed by a third straight line passing through a first first connecting shaft and the second connecting portion between the respective link, connected to the first first

15

connecting shaft, and the second member, and a fourth straight line passing through a second first connecting shaft and the second connecting portion between the respective link, connected to the second first connecting shaft, and the second member.

2. The hand grip mechanism of claim 1, wherein in each grip link, the second connecting portion between the second member and the link is provided farther inward than a central axis of the hand grip when viewed from the grip link.

3. A drive mechanism configured by the hand grip mechanism of claim 1,

wherein a pressure chamber is formed by the first member and the second member.

4. An air pump comprising the drive mechanism of claim 3.

5. The air pump of claim 4, further comprising: a flow path switching mechanism including an actuating member provided with a valve body, and a housing provided with a valve chamber configured to house the

5

10

15

16

valve body in an advanceable and retractable manner between a pressurized position and a depressurized position, the valve body being configured to enable an intake port to communicate with an inlet and enable an outlet to communicate with a connecting port in the pressurized position, and to enable the connecting port to communicate with the inlet and enable the outlet to communicate with an exhaust port in the depressurized position,

wherein the pressure chamber is configured to communicate with the inlet and the outlet.

6. The air pump of claim 5, further comprising: a vent opening configured to communicate with the connecting port of the flow path switching mechanism both when the actuating member is in the pressurized position and in the depressurized position; and an opening and closing member configured to open and close the vent opening.
